UNITED STATES PATENT OFFICE.

CARL D. VANCE AND FOREST G. BOWMAN, OF DAYTON, OHIO.

DOOR CONSTRUCTION.

Application filed January 20, 1922. Serial No. 530,713.

To all whom it may concern:

Be it known that we, CARL D. VANCE and FOREST G. BOWMAN, citizens of the United States, residing at Dayton, in the county 5 of Montgomery and State of Ohio, have invented certain new and useful Improvements in Door Constructions and the like, of which the following is a specification, reference being had therein to the accompanying drawings.

This invention relates to improvements in door construction, having particular reference to sliding folding doors of the accordion type,—the invention being especially adaptable to doors of this character 15 for closing wide, openings where the use of partition posts or columns would interfere with the operation of the doors and with the entrances and exits of buildings where 20 the doors are used.

An object of the invention, therefore, is to provide doors of this character suitable for door openings of any width or length,—there being no limit, practically, to the 25 adaptability of our improved doors in this respect,—the doors being arranged, preferably, in separate units to facilitate operation thereof.

It is a further object of our invention to 30 provide doors and means for their support and operation whereby the doors will be adapted to be moved entirely outside the plane of the door entrance, as adjacent the side or around or beyond the corner of the 35 building in connection with which the doors are used, thus leaving the door opening entirely clear.

An object of the invention is to provide 40 an improved door construction as to the means for supporting the weight of the doors, and for maintaining their balance or equilibrium, thus to insure ease of operation and normal movement of the doors irrespective of their size and weight, and the number 45 of units used to a single opening.

In the accompanying drawings:

Fig. 1 is a front elevation of two opposite door sections, illustrating a construction typical of the accordion type of folding 50 doors, and including details of the present invention;

Fig. 2 is a bottom view of the construction shown in Fig. 1;

Fig. 3 is a top view of a folded unit of 55 the doors;

Fig. 4 is a detail view, in side elevation, of the door supporting mechanism;

Fig. 5 is a detail view, in end elevation and in section, of the door supporting mechanism, and

Fig. 6 is a detail view, in end elevation of the door head mechanism.

As here shown in Fig. 3, each of the door units comprises a number, preferably six, of door sections —1, adjacent sections 60 of each unit being joined one to the other at both edges by off-set hinges —2, thus permitting the door sections to be folded parallel one with another, and the unit to be shifted as a whole in either direction. 70

The head construction of the doors, as here shown, consists of the opposite guides or tracks —4 supported in the overhead frame structure, in any suitable manner, as on the beams —5 by means of bolts —6; 75 and a guide roller —7 secured to each door section, on the top edge, adjacent the inner corner thereof, as the doors are folded, by means of a bracket or housing —8 and a bearing —9 upon which the guide roller 80 rotates.

The door supporting mechanism, as here shown, in detail Figs. —4 and —5, consists of a T-rail constituting a track —10 upon which the doors can be shifted in 85 either direction; a wheel or roller —11 secured to each door section adjacent the inner corner thereof, as the doors are folded, by means of opposite plates —12 and —13, which serve to strengthen the corners of the 90 door sections, and as a means for supporting a bearing sleeve —14 which is adapted to receive a pivot stem —15 of a bifurcated bearing bracket and wheel housing —16 in which the wheel —11 is supported,—the 95 wheel thus being free to travel on the track —10 and to turn, with the bracket —16 in the pivot bearing —14 —15.

As here shown, a ball bearing —17 is interposed between the wheel housing and 100 plate —12,—a portion of the edge of the plate being turned under to overlap the edge of the door as indicated at —18 in Fig. 5, and ball bearings —19 are preferably used on opposite sides of the door supporting wheel —11, thus to effect easy operation of the doors. The remaining portion of the edge of plate —12 overlaps the lower edge of the door section as at —20 to protect the edge and further strengthen 110

the construction, and the lower portion of plate —13 is flared outwardly as at —21 to provide clearance for turning the door sections at right-angles relative to wheels —11, thus to permit of folding the sections of each unit as illustrated in Fig. 3.

As here shown, the T-rail —10 projects slightly above the floor line —22. It will be understood, however, that this showing is for illustrative purposes only, and that the top of the rail may be either above or below the surface of the floor as may be desired or determined by the entrance and exit requirements.

From the foregoing detailed description, the construction and operation of our improved doors will be readily understood. It will be observed that the doors as a whole constitute a well balanced construction, that the construction is adapted to folding doors of any practical height and length, that the door opening is entirely free of obstructing posts or columns, that the weight of the doors, whether the doors are open or closed, is supported entirely from the bottom on the track —10, that the doors can be moved in either direction on the track, and, where it is desired and provision is made for it by the proper placing and extension of track —10 and the overhead guides, that the doors can be moved entirely out of the way beyond the door opening, also that the construction of the doors and door supporting means is such as will give both ease and freedom of operation, and that the structure as a whole is of simple and substantial construction.

Having described our invention, we claim:

1. In folding doors, including in combination with suitable head construction for the doors, a door unit consisting of a plurality of door sections hinged one to another, and adapted to be folded substantially parallel one with another, each door section having its lower inner corner, as the doors are folded, cut away and re-inforced, by metal plates secured to opposite sides of the door, one of the plates having an edge thereof turned under and overlapping the lower edge of the cut away portion of the door, the other plate being flared outwardly opposite said cut away portion, a wheel disposed in said cut away portion and having a bearing reinforced by the overlapping edge of the first named plate, the door section being supported on said wheel and adapted to turn on said bearing as a pivot, as the door sections are moved into said parallel relation, a track adapted to support the door

sections from beneath and over which said wheels are adapted to travel as the doors are operated.

2. In folding doors, including in combination with suitable head construction for the doors, a door unit consisting of a plurality of door sections hinged one to another, and adapted to be folded substantially parallel one with another, each door section having its lower inner corner, as the doors are folded, cut away and reinforced by metal plates secured one to the other from opposite sides of the door, one of the plates having an edge thereof turned under and overlapping the lower edge of the door and the lower edge of said cut away portion, the other plate being flared outwardly opposite said cut away portion and acting as a guard, a wheel disposed in the cut away portion upon which the door section is supported and adapted to turn as a pivot, as the door sections are moved into said parallel relation, a track adapted to support the door sections from beneath and over which said wheels are adapted to travel as the doors are operated.

3. In folding doors, including in combination with suitable head construction for the doors, a door unit consisting of a plurality of door sections hinged one to another, and adapted to be folded substantially parallel one with another, each door section having its lower inner corner, as the doors are folded, cut away and reinforced, by metal plates secured one to the other from opposite sides of the door section and having their corresponding edges arranged flush with the side and bottom edges of the said section, one of the plates having an edge thereof turned under, overlapping the lower edge of the door, said other plate being flared outwardly opposite said cut away portion to provide a guard, a wheel supported in a bifurcated housing in said cut away portion and having a sleeve bearing supported in the overlapping portion of the first named plate, said door section being supported on said wheel and adapted to turn on said bearing as a pivot, as the door sections are moved into said parallel relation, a track adapted to support the door sections from beneath and over which said wheels travel as the doors are operated.

In testimony whereof, we affix our signatures.

CARL D. VANCE.
FOREST G. BOWMAN.
